H. SCHLÜTER,
POST OF CONCRETE OR OTHER MATERIAL.
APPLICATION FILED JULY 25, 1918.

1,299,787.

Patented Apr. 8, 1919.

UNITED STATES PATENT OFFICE.

HUGO SCHLUTER, OF LOS ANGELES, CALIFORNIA.

POST OF CONCRETE OR OTHER MATERIAL.

1,299,787.

Specification of Letters Patent.

Patented Apr. 8, 1919.

Application filed July 25, 1918. Serial No. 246,735.

To all whom it may concern:

Be it known that I, HUGO SCHLUTER, a citizen of the United States, residing at Los Angeles, in the county of Los Angeles, 5 State of California, have invented new and useful Improvements in Posts of Concrete or other Material, of which the following is a specification.

This invention relates to concrete or other 10 posts or similar elongated objects, such as posts or poles which are commonly used for electric transmission, etc. It is a particular object of this invention to provide a construction, readily adapted to be made 15 in concrete, whereby a long article, such as a post or pole, may be originally made and shipped in sections and assembled from those sections to form a strong post of any desired length; and it is a further object of 20 this invention to provide such a construction in a simple and effective form.

With these objects in view there are other 25 objects of the invention; and all such objects will be better understood from a following detailed description of preferred forms of devices embodying the invention, reference being had for this purpose to the accompanying drawings in which—

Figure 1 is an elevation of one form of 30 my improved post; Fig. 2 is an enlarged cross section of the same; Fig. 3 is an elevation of another form of my improved post; Fig. 4 is an enlarged cross section of the same; Fig. 5 is a similar enlarged cross section showing a modified form of construction; Fig. 6 is a longitudinal section showing another modification in the structure of my post; and Fig. 7 is a cross section of the same.

40 Referring now first to Figs. 1 and 2, I show a post made up of a plurality of sections (any number of sections, the number depending upon the length of the post). Each of these sections comprises, in this 45 form of post, a hollow cylindrical casting of concrete C which may be reinforced with wire netting 10, and also may be reinforced with longitudinal rods 11. These longitudinal rods 11 afford anchors to which the 50 eye bolts 12 are anchored. Eye bolts 12 extend out to the outer surface of the concrete body and are provided with nuts 13 on their outer ends. Reinforcing rods 11 and eye bolts 12 may be of any suitable number, 55 preferably three or more, and shown in this construction as being four in number. Lon-

gitudinally along the outer surface of each of the concrete sections I run grooves 15; and in these grooves, when a post is assembled, metal strips or bars 16 are laid from 60 end to end of the whole length of the post. These metal bars are, or have been previously, provided with spaced holes for the bolts 12; and the nuts 13 are screwed down outside the metal bars to hold them in place. 65 The longitudinal metal bars hold the concrete section together, end to end, and provide longitudinal tension members on the outside of the post which prevent any bending of the post. 70

The bolts and nuts 12 and 13 may also be used for the purpose of securing steps 20 to the post and for securing a cross beam 21 and braces 22. A cap 23 of any suitable material may be placed on the top of the 75 finished post. This cap may be used as a lamp base, etc.

In Figs. 3 and 4 I show a similar construction in which the concrete sections C¹ are semi-cylindrical in form and are assembled in break-joint fashion so that no transverse joint extends completely across the whole post. Each semi-cylindrical section C¹ has along one edge a bead 25 and along the other edge a corresponding groove 85 26, these beads and grooves interfitting when the sections are assembled. It will be noted that the opposing interfitting sections are duplicates of each other. Each section C¹ has a single superficial groove 15^a; and longitudinal bars 16^a are laid in these 90 grooves. Bolts 30 pass transversely through the sections and through the bars 16^a, having nuts and collars 31 and 31^a outside the bars. The nut 31 is screwed up tightly to 95 hold the sections laterally together; and the longitudinal bars 16^a perform the same office as before, holding the sections together longitudinally and in providing longitudinal tension members at the outside surface 100 of the assembled posts. Liquid cement, asphaltum, or any suitable substance may be inserted in a joint between ribs 25 and grooves 26 so as to make the completed post water-tight. The bolts 30 may be extended 105 to form steps 30^a; and the bolts 30 may also be used, as in the other form herein explained, for securing the cross-arm 21 and bases 22.

In Fig. 5 I show a further modification of 110 the form shown in Fig. 4 in which each section C¹ is provided with two grooves 26, and

a pair of round joint-making members 25^a may be used to fit in the opposing grooves 26. These joint-making members may be of metal, wood, concrete, or any suitable material. In fact, it will be understood that my post construction may be made of any suitable material, not being limited to concrete, although preferably of that material.

In Fig. 6 I show a further modification 10 of the form shown in Fig. 5; wherein the bolts are not extended clear through the post but are provided as anchor bolts 30^a which are cast into the concrete of the half sections C¹. Each bolt 30^a has on its inner 15 end an inclined foot 30^b, and the inclined feet of opposing bolts are adapted to act as inclined planes to draw the half sections laterally together when the sections are slid longitudinally of each other; as they may 20 be so slid and held in alinement by their tongue and groove engagement. In this form, the side bars 16^a hold the sections in proper longitudinal position after assembly.

In erecting my poles the sections may be 25 made at a factory and carried to the place of use. The pole may be assembled wholly or partly on the ground and then raised and set; or it may be wholly assembled in a vertical position. The lower end may be set in 30 a concrete base 40; and the interior of the erected post may be filled with concrete as indicated at 41, either partly or wholly to the top of the pole. A central reinforcement or anchor rod 42 may be run up through the 35 pole from the foundation 40. The completed pole thus becomes very stable and strong. This filling also prevents movement of the parts 30^a, 30^b (Figs. 6 and 7) and of the bolts 30 (Figs. 3 and 4).

40 Having now described a preferred form of my invention, I claim:

1. In a sectional post, a plurality of post sections adapted to be joined end to end, said sections being substantially semi-cylindrical in formation and being assembled in

break joint fashion; tension and connecting members extending longitudinally on the exterior surface of the several sections; and transverse rods tying overlapping sections and said connecting members together. 50

2. In a sectional post, a plurality of post sections adapted to be joined end to end, said sections being substantially semi-cylindrical in formation and being assembled in break joint fashion; tension and connecting 55 members extending longitudinally on the exterior surface of the several sections, said sections having longitudinal superficial grooves in which said connecting members lie; and transverse rods tying overlapping sections 60 and said connecting members together.

3. In a sectional post, the combination of a plurality of hollow post sections adapted to be joined end to end, longitudinal tension and connecting members extending longitudinally of the sections, transverse bolts for holding the longitudinal members to the sections, and a filling of concrete for the interior of the sections; said sections being semi-cylindrical in form and assembled to form 70 a cylindrical post, and said bolts extending across the hollow interior and embedded in the concrete filling.

4. In a sectional post, a plurality of part-cylindrical sections joined end to end in overlapping break-joint fashion, a plurality of tension - and - connection bars extending longitudinally on the exterior surface of the several sections, and transverse bolts each extending through the longitudinal bars and 75 through two of said sections and tying the bars and the overlapping sections all together.

In witness that I claim the foregoing I have hereunto subscribed my name this 18th day of July, 1918. 85

HUGO SCHLUTER.

Witness:

VIRGINIA I. BERINGER.
